N. PELLIGREEN

LADDER

Filed Aug. 25, 1924

Patented Dec. 22, 1925.

UNITED STATES PATENT OFFICE.

NICHOLAS PELLIGREEN, OF ST. LOUIS, MISSOURI.

LADDER.

Application filed August 25, 1924. Serial No. 733,861.

To all whom it may concern:

Be it known that I, NICHOLAS PELLIGREEN, a citizen of the United States, and resident of the city of St. Louis, and State of Missouri, have invented certain new and useful Improvements in Ladders, of which the following is a specification containing a full, clear, and exact description, reference being had to the accompanying drawings, forming a part thereof.

My invention relates to improvements in ladders and has for its primary object a ladder which is provided with a folding stand whereby the same may be held in vertical position.

A further object is to construct a ladder provided with a folding stand, which stand is adjustable so that the ladder may be held vertically on uneven surfaces making my device especially useful on sidewalks which slope and also for fruit-pickers.

A still further object is to construct a ladder provided with a stand for supporting the same vertically, in which the stand can be collapsed and the ladder used in the same manner as an ordinary ladder.

My improved ladder is also used for paper hangers, painters and house cleaners as a scaffold can be readily supported on the rungs of two spaced apart ladders thus affording a platform for the workmen.

In the drawings:

Fig. 1 is a perspective view of my improved ladder showing the same supported in vertical position and illustrating the folding up of the legs by dotted lines;

Fig. 2 is an enlarged section taken on the line 2—2 of Fig. 1; and

Fig. 3 is a horizontal section taken on the line 3—3 of Fig. 2.

In carrying out my device I employ a ladder having side members 4, these members are spaced apart as illustrated and have secured therein rungs 5. The side members 4 are also provided with slots 6 and 7, the slots 6 in both members 4 being opposite each other when the ladder is assembled, as are also the slots 7. The slots 6 and 7 extend longitudinally of the members 4 and are also spaced apart and preferably at such a distance as to permit a rung to be inserted therebetween. Extending through the slots 6 is a rod 8 which is screw threaded as at 9 so as to receive a thumb nut 10. The opposite end of the rod 8 is provided with a head. Surrounding the

rod 8 and located between the members 4 is a pipe 11, this pipe 11 is designed to take the place of one of the rounds or rungs of the ladder.

Pivotaly supported on the rod 8 are legs 12, these legs are spaced apart from the members 4 by means of a washer 13. On the outside of the legs 12 is placed a second washer 14 against which the thumb nut 10 and the head, formed on the opposite ends of the rod 8, bear respectively. Secured to the lower end of the legs 12 are chains 15, the opposite ends of the chains are each provided with a hook 16 which is designed to be secured in an eye 17 carried by each of the members 4. In place of the hook 16, a snap fastener may be used, if found desirable. The purpose of using the snap fastener or hook 16 is to permit the chain to be disengaged from the eye 17 so that the legs 12 may be folded upward along the members 4, as indicated by dotted lines in Fig. 1, and the chains wrapped around the members 4 thus holding the legs 12 in folded position.

Passing through the slots 7 is a rod 18 which is constructed in the same manner as the rod 8 and is provided with the thumb nut 10 and with washers 13 and 14. The rod 18 extends through the legs 19 at a point intermediate their ends, leaving projections 20 above the rod 18, the ends of which are designed to contact with the edges of the legs 12 thereby preventing any collapsing of the legs.

Secured to each of the eyes 17 is one end of a chain 21, the opposite end of which is secured to one of the legs 19. The purpose of the chains 15 and 21 is to permit the spreading of the legs and thus prevent any possibility of the collapse of the ladder.

The setting up of my device is as follows:

The hook or securing means 16 of the chains 15 is first fastened to the eyes 17, after which the legs 19 are pulled out, as indicated in Fig. 1, and in so doing the ends 20 of the legs 19 contact with the edges of the legs 12 forcing them out in the position shown in Fig. 1. This position assures a vertical arrangement of the ladder with the lower ends of the side members 4 resting on the ground. The thumb nuts 10 are then tightened up on the rods 8 and 18 thus securely holding the legs in extended position and preventing any collapse.

The slots 6 and 7 formed in each of the side members 4 permit a certain amount of vertical adjustment of the legs 12 and 19 on the same side of the ladder thereby 5 permitting the same to rest on an inclined surface, as for instance, a sidewalk which naturally slopes toward the street. In this event, however, it is preferable to block up under the side members 4 so as to form 10 a firm support for the ladder while the same is being held in vertical position. Were this blocking up not done, the side members 4 toward the street would not be supported on the ground at all but only by 15 the friction set up through the tightening of the thumb nuts 10.

The pipes 11 which surround the rods 8 and 18 prevent the side members from being drawn inward due to the pressure set 20 up when the thumb nut 10 is tightened and also serve as rounds for the ladder.

When it is desired to use my ladder in the ordinary manner, the legs 12 are swung up into the position indicated by dotted lines 25 in Fig. 1, and secured in said position by means of the chains 15, then the upper end of the ladder can be leaned against the wall or other support.

The washers 13 prevent the legs 12 and 30 19 from contacting with the side members 4 thus allowing their ready pivoting and at the same time eliminate friction between the legs and the side members. It is also possible to adjust the legs 12 and 19 on the 35 same side of the ladder independently of each other, this is sometimes necessary especially on uneven ground due to the fact that one leg will have to be fitted into a

depression in the ground or surface, and by this independent adjustment great stability can be given the ladder and all possibility of rocking eliminated. 40

The legs 12 and 19 are preferably so secured to the side members 4 that their lower ends will pass the eye 17, this is especially 45 desirable with the legs 19 so that when the legs 12 are folded upward, either side of the upper end of the ladder can be rested against a support and the legs 19 swung out of the way so that the bottom end of 50 the ladder can rest on the ground.

Having fully described my invention, what I claim is:—

A ladder comprising a pair of side members having rungs therebetween and having 55 a pair of spaced apart longitudinally extending slots in each of said side members, rods extending through said slots, a tube surrounding each of said rods and located between the side members and adapted to 60 serve as a rung, a leg pivotally mounted on each end of one of said rods and located adjacent one of said side members, a second pair of legs pivoted intermediate their ends to the remaining rod and located adjacent 65 the outside of the respective side members, one end of each of said last mentioned legs adapted to contact with an edge of the first mentioned legs for supporting the same, means carried by the rods whereby said legs 70 may be secured to said side members against movement, and flexible means for limiting the spreading of said legs.

In testimony whereof, I have signed my name to this specification.

NICHOLAS PELLIGREEN.
